FOOT ACTUATED ROTARY SWITCH

Nobel H. Koertge, Glen Ellyn, and Edward L. Rucks, Aurora, Ill., assignors to Furnas Electric Company, Batavia, Ill., a corporation of Illinois

Application May 24, 1947, Serial No. 750,338

7 Claims. (Cl. 260—66)

1
The present invention relates generally to improvements in electric switches and the actuation thereof, and relates more particularly to improvements in the construction and operation of foot actuated rotary switches for controlling diverse types of electrical equipment.

A primary object of our invention is to provide an improved foot actuated rotary switch which is extremely simple, compact and durable in construction, and which is moreover highly efficient in operation.

A more specific object of this invention is to provide an improved actuating mechanism for rotary reversing switches which may be conveniently controlled by foot in a simple and most natural manner, and wherein the foot movement naturally conforms with the forward and reverse positioning of the switch.

Another specific object of the invention is to provide an improved pedal actuated rotary switch assembly which is highly flexible in its adaptations, and which is adapted for diverse uses to control either direct or alternating current electrical apparatus.

Another specific object of the invention is to provide an improved foot actuated device for rotary reversing switches which is positive in action and wherein the switch is automatically returned to neutral or off position upon removal of pressure from the pedal.

A further specific object of our present invention is to provide an improved foot actuated rotary reversing switch assembly which may be conveniently mounted in confined spaces and in various positions as conditions require, and wherein movement of the foot pedal is positively limited in either forward or reverse direction.

An additional specific object of the present invention is to provide an improved foot actuated rotary reversing switch wherein the switch contacts are quickly and effectively engaged and disconnected, and which comprises relatively few parts which may be readily manufactured of available materials and assembled and soldered at moderate cost.

Still another specific object of the present invention is to provide an improved foot actuated rotary switch assembly which may be readily manipulated in a safe and simple manner by a novice, which is durable in construction and adapted for long usage, and wherein all parts are readily accessible and may be quickly and easily dismantled and reassembled.

These and other specific objects and advantages of the present invention will be apparent from the following detailed description.

2
A clear conception of the several features constituting our present improvement, and of the mode of constructing and of utilizing a typical foot actuated rotary reversing switch embodying the invention, may be had by referring to the drawing accompanying and forming a part of this specification wherein like reference characters designate the same or similar parts in the various views.

Fig. 1 is a perspective view of the improved foot actuated mechanism as applied to a typical rotary reversing switch adapted for either direct current, or one, two, or three phase circuits;

Fig. 2 is a longitudinal vertical section through the actuating mechanism, taken along the line 2—2 of Fig. 3; and

Fig. 3 is an end view of the complete assemblage.

While the invention has been shown and described herein as being especially applicable to a rotary reversing switch of a particular type, it is not our desire or intention to unnecessarily restrict the scope or utility of the improved features by reason of such limited embodiment, and the typical rotary reversing switch shown herein by way of illustration is generally of the type fully shown and described in the copending application of William C. Furnas and Edward L. Rucks, Serial No. 715,642, filed December 9, 1946.

Referring to the drawing, the improved foot actuated rotary reversing switch assemblage shown therein comprises, in general, a substantially flat horizontal base plate 5 having an upwardly projecting switch supporting bracket 6 suitably secured to one corner thereof as by welding or riveting; a rotary reversing switch 7 mounted upon the bracket 6, the switch 7 having the usual movable contact carrying rotor, not shown, confined thereto and carried by an outwardly projecting control shaft 8 having a square protruding end portion; a bifurcated member or lever 9 provided with a square hole 10 snugly fitting the square end of the shaft 8 and having an elongated radial slot 11 formed by the bifurcations; a U-shaped bracket 12 rigidly secured in any suitable manner to the medial portion of the base plate 5, the upwardly projecting spaced ears 13 of the bracket 12 having aligned circular openings therethrough adapted to receive a shaft 15; a pedal 16 provided with medial depending lugs or ears 17 having aligned openings pierced by the shaft 15 to provide a pivotal mounting therefor, the pedal 16 being also provided with a laterally projecting pin 18 adjacent an end thereof and extending through the slot 11 of the lever 9, and a pair of upright stop posts

19, 20 suitably secured to the base plate 5 forwardly and rearwardly respectively of the pedal supporting bracket 12, the stop posts 19, 20 being independently cooperable with the pedal 16, as will hereinafter more clearly appear, to limit the pivotal movement thereof in a clockwise and counterclockwise direction respectively.

The pedal 16 is preferably formed with a series of transverse upper ribs 21 to provide a roughened foot engaging surface, and is also normally maintained in slightly tilted position with respect to the horizontal base plate 5 so as to most naturally conform with the foot position of the operator. To compensate for the normal tilt of the pedal 16 and to provide for the cooperation of the stops 19, 20 with the pedal, the pedal 16 is formed with depending front and rear bosses 22, 23 respectively having recesses or sockets 24, 25 therein adapted to receive the free upper ends of the respective fixed posts 19, 20. The bosses 22, 23 are of different heights in order to compensate for the inclination of the pedal and the recesses 24, 25 are of approximately the same depth, the bottoms of these recesses being adapted to abut against the upper enlarged end heads 26, 27 of the respective adjacent posts 19, 20 which are of equal height. The difference in length of the bosses 22, 23 thus alone compensates for the pedal inclination and permits the use of similar posts 19, 20 for limiting the swing of the pedal in either direction.

In some cases, it is additionally desirable to provide means for automatically returning the pedal 16 to normal inclined position, as shown in the drawing, with the end heads 26, 27 of the posts 19, 20 respectively both out of contact with the bottoms of the respective recesses 24, 25; and this is readily accomplished in a simple manner by the provision of helical compression springs 28, 29 respectively embracing the posts 19, 20 and confined between the base plate 5 and the respective washers 30, 31 which are constantly urged upwardly against the lower surfaces of the bosses 22, 23 respectively. By reason of the fact that the bosses 22, 23 are of different lengths to compensate for the normal inclination of the pedal 16, the helical springs 28, 29 may be of like length and strength and therefore interchangeable; and these springs are retained in position upon the posts 19, 20 by the respective washers 30, 31 which are cooperable with the enlarged end heads 26, 27 respectively of the posts.

The shaft 15 forming the pivot for the pedal 16 may be conveniently retained in position on the bracket 12 by means of split retaining rings 32 or the like, and the driven pin 18 may be secured to the pedal in any suitable manner as by threaded coaction with a tapped hole 33 in the lug 34. The various parts of the unit may be readily manufactured of suitable durable materials such as sheet metal and/or castings, and these parts may be quickly assembled in an obvious manner. As hereinabove set forth, the stop posts 19, 20 as well as the compression springs 28, 29 and washers 30, 31 may all be made similar and interchangeable, and the posts 19, 20 may be screw-threaded or otherwise suitably secured to the base plate 5.

The typical rotary reversing switch 7 shown herein is provided with movable contacts carried by a rotor which is in turn mounted upon the shaft 8, and this switch is, of course, provided with the usual conduit outlets and may be used with direct current or one, two, or three phase circuits. The lever 9 is so mounted on the shaft 8 that when it is in the position shown in the

drawing, the contacts are open and the switch is in off position with the pedal 16 maintained in neutral and normal inclined position by the springs 28, 29 which are of like strength and under equal pressure; and when the rotor control shaft 8 is rotated in a clockwise direction, the contacts are closed in forward position while counterclockwise rotation of the shaft 8 causes closing of the contacts in reverse position.

It is therefore apparent that when the improved foot actuated rotary switch has been properly assembled, installed, and positioned on the floor or other locality convenient to the operator, the operation is as follows: The switch is normally maintained in off position as shown by the counter-action of the springs 28, 29. To effect closing of the switch contacts in a forward direction; it is merely necessary for the operator to apply downward foot pressure to the front or toe end of the pedal, whereupon the pedal 16 is rotated clockwise to compress the spring 28 and expand the spring 29 until the swinging of the pedal is positively stopped by the post 19, the end head 26 of which is caused to contact the bottom of the recess 24 in the boss 22. This pedal movement carries the pin 18 downwardly, causing the lever 9 and shaft 8 to which the lever is keyed to swing or rock in a clockwise direction, the pin 18 being caused to travel within the radial slot 11 of the lever 9 during such movement. Thus, the contacts are rotated toward closed forward position, and the height of the stop post 19 is such that the above-described movement is positively stopped when the contacts are fully closed in forward position. Upon release of pressure from the pedal 16, the springs 28, 29 cooperate in an obvious manner to automatically return the pedal and its associated parts, including the lever 9, shaft 8, and the movable switch contacts, to normal off position. Obviously, to close the switch contacts in a reverse direction, the operation is reversed with downward pressure being applied to the rear or heel end of the pedal, the pedal 16 being thereby rotated counterclockwise to compress the spring 29 and permit expansion of the spring 28 until the pedal is positively stopped by the post 20. During such reverse movement, the pin 18 is carried upwardly by the pedal, causing the lever 9 and shaft 8 to rock in a counterclockwise direction with the pin travelling along the slot 11 of the lever 9. The movable contacts are thereby rotated toward closed reverse position, and such movement is positively stopped by the limit pin or post 20 when the reverse contacts are fully closed. As above set forth, the parts are automatically returned to normal position by the springs 28, 29 upon release of pressure on the pedal 16.

From the foregoing detailed description, it is apparent that the present invention provides an improved foot actuated rotary switch assemblage which is extremely simple and compact in construction, highly efficient in operation, and adapted for diverse uses. The improved assemblage is composed of relatively few parts, many of which are interchangeable, which may be readily formed in an obvious manner of available materials and quickly assembled or dismantled. The pedal 16 in normal position is inclined at an angle to the horizontal for convenience of the operator to most naturally conform to the position of the foot, and the pedal and switch are furthermore actuated to forward and reverse positions by the most natural foot movements. If desired, the springs 28, 29 may be omitted, and

a foot actuated switch assemblage will thereby be provided wherein the switch may be entirely manually actuated to forward, off, or reverse position at the will of the operator, the switch contacts remaining in the various positions upon release of pressure from the pedal. The improved unit is extremely durable in construction and may be safely operated by a novice, and all parts of the assemblage readily accessible for inspection, cleaning, and/or repair. The stop posts 18, 19, 20, 21, 22, 23, 24, 25, 26, 27, 28, 29, 30, 31, 32, 33, 34, 35, 36, 37, 38, 39, 40, 41, 42, 43, 44, 45, 46, 47, 48, 49, 50, 51, 52, 53, 54, 55, 56, 57, 58, 59, 60, 61, 62, 63, 64, 65, 66, 67, 68, 69, 70, 71, 72, 73, 74, 75, 76, 77, 78, 79, 80, 81, 82, 83, 84, 85, 86, 87, 88, 89, 90, 91, 92, 93, 94, 95, 96, 97, 98, 99, 100, 101, 102, 103, 104, 105, 106, 107, 108, 109, 110, 111, 112, 113, 114, 115, 116, 117, 118, 119, 120, 121, 122, 123, 124, 125, 126, 127, 128, 129, 130, 131, 132, 133, 134, 135, 136, 137, 138, 139, 140, 141, 142, 143, 144, 145, 146, 147, 148, 149, 150, 151, 152, 153, 154, 155, 156, 157, 158, 159, 160, 161, 162, 163, 164, 165, 166, 167, 168, 169, 170, 171, 172, 173, 174, 175, 176, 177, 178, 179, 180, 181, 182, 183, 184, 185, 186, 187, 188, 189, 190, 191, 192, 193, 194, 195, 196, 197, 198, 199, 200, 201, 202, 203, 204, 205, 206, 207, 208, 209, 210, 211, 212, 213, 214, 215, 216, 217, 218, 219, 220, 221, 222, 223, 224, 225, 226, 227, 228, 229, 230, 231, 232, 233, 234, 235, 236, 237, 238, 239, 240, 241, 242, 243, 244, 245, 246, 247, 248, 249, 250, 251, 252, 253, 254, 255, 256, 257, 258, 259, 260, 261, 262, 263, 264, 265, 266, 267, 268, 269, 270, 271, 272, 273, 274, 275, 276, 277, 278, 279, 280, 281, 282, 283, 284, 285, 286, 287, 288, 289, 290, 291, 292, 293, 294, 295, 296, 297, 298, 299, 300, 301, 302, 303, 304, 305, 306, 307, 308, 309, 310, 311, 312, 313, 314, 315, 316, 317, 318, 319, 320, 321, 322, 323, 324, 325, 326, 327, 328, 329, 330, 331, 332, 333, 334, 335, 336, 337, 338, 339, 340, 341, 342, 343, 344, 345, 346, 347, 348, 349, 350, 351, 352, 353, 354, 355, 356, 357, 358, 359, 360, 361, 362, 363, 364, 365, 366, 367, 368, 369, 370, 371, 372, 373, 374, 375, 376, 377, 378, 379, 380, 381, 382, 383, 384, 385, 386, 387, 388, 389, 390, 391, 392, 393, 394, 395, 396, 397, 398, 399, 400, 401, 402, 403, 404, 405, 406, 407, 408, 409, 410, 411, 412, 413, 414, 415, 416, 417, 418, 419, 420, 421, 422, 423, 424, 425, 426, 427, 428, 429, 430, 431, 432, 433, 434, 435, 436, 437, 438, 439, 440, 441, 442, 443, 444, 445, 446, 447, 448, 449, 450, 451, 452, 453, 454, 455, 456, 457, 458, 459, 460, 461, 462, 463, 464, 465, 466, 467, 468, 469, 470, 471, 472, 473, 474, 475, 476, 477, 478, 479, 480, 481, 482, 483, 484, 485, 486, 487, 488, 489, 490, 491, 492, 493, 494, 495, 496, 497, 498, 499, 500, 501, 502, 503, 504, 505, 506, 507, 508, 509, 510, 511, 512, 513, 514, 515, 516, 517, 518, 519, 520, 521, 522, 523, 524, 525, 526, 527, 528, 529, 530, 531, 532, 533, 534, 535, 536, 537, 538, 539, 540, 541, 542, 543, 544, 545, 546, 547, 548, 549, 550, 551, 552, 553, 554, 555, 556, 557, 558, 559, 560, 561, 562, 563, 564, 565, 566, 567, 568, 569, 561, 562, 563, 564, 565, 566, 567, 568, 569, 570, 571, 572, 573, 574, 575, 576, 577, 578, 579, 580, 581, 582, 583, 584, 585, 586, 587, 588, 589, 581, 582, 583, 584, 585, 586, 587, 588, 589, 590, 591, 592, 593, 594, 595, 596, 597, 598, 599, 591, 592, 593, 594, 595, 596, 597, 598, 599, 600, 601, 602, 603, 604, 605, 606, 607, 608, 609, 601, 602, 603, 604, 605, 606, 607, 608, 609, 610, 611, 612, 613, 614, 615, 616, 617, 618, 619, 611, 612, 613, 614, 615, 616, 617, 618, 619, 620, 621, 622, 623, 624, 625, 626, 627, 628, 629, 621, 622, 623, 624, 625, 626, 627, 628, 629, 630, 631, 632, 633, 634, 635, 636, 637, 638, 639, 631, 632, 633, 634, 635, 636, 637, 638, 639, 640, 641, 642, 643, 644, 645, 646, 647, 648, 649, 641, 642, 643, 644, 645, 646, 647, 648, 649, 650, 651, 652, 653, 654, 655, 656, 657, 658, 659, 651, 652, 653, 654, 655, 656, 657, 658, 659, 660, 661, 662, 663, 664, 665, 666, 667, 668, 669, 661, 662, 663, 664, 665, 666, 667, 668, 669, 670, 671, 672, 673, 674, 675, 676, 677, 678, 679, 671, 672, 673, 674, 675, 676, 677, 678, 679, 680, 681, 682, 683, 684, 685, 686, 687, 688, 689, 681, 682, 683, 684, 685, 686, 687, 688, 689, 690, 691, 692, 693, 694, 695, 696, 697, 698, 699, 691, 692, 693, 694, 695, 696, 697, 698, 699, 700, 701, 702, 703, 704, 705, 706, 707, 708, 709, 701, 702, 703, 704, 705, 706, 707, 708, 709, 710, 711, 712, 713, 714, 715, 716, 717, 718, 719, 711, 712, 713, 714, 715, 716, 717, 718, 719, 720, 721, 722, 723, 724, 725, 726, 727, 728, 729, 721, 722, 723, 724, 725, 726, 727, 728, 729, 730, 731, 732, 733, 734, 735, 736, 737, 738, 739, 731, 732, 733, 734, 735, 736, 737, 738, 739, 740, 741, 742, 743, 744, 745, 746, 747, 748, 749, 741, 742, 743, 744, 745, 746, 747, 748, 749, 750, 751, 752, 753, 754, 755, 756, 757, 758, 759, 751, 752, 753, 754, 755, 756, 757, 758, 759, 760, 761, 762, 763, 764, 765, 766, 767, 768, 769, 761, 762, 763, 764, 765, 766, 767, 768, 769, 770, 771, 772, 773, 774, 775, 776, 777, 778, 779, 771, 772, 773, 774, 775, 776, 777, 778, 779, 780, 781, 782, 783, 784, 785, 786, 787, 788, 789, 781, 782, 783, 784, 785, 786, 787, 788, 789, 790, 791, 792, 793, 794, 795, 796, 797, 798, 799, 791, 792, 793, 794, 795, 796, 797, 798, 799, 800, 801, 802, 803, 804, 805, 806, 807, 808, 809, 801, 802, 803, 804, 805, 806, 807, 808, 809, 810, 811, 812, 813, 814, 815, 816, 817, 818, 819, 811, 812, 813, 814, 815, 816, 817, 818, 819, 820, 821, 822, 823, 824, 825, 826, 827, 828, 829, 821, 822, 823, 824, 825, 826, 827, 828, 829, 830, 831, 832, 833, 834, 835, 836, 1333, 1334, 1335, 1336, 1337, 1338, 1339, 1331, 1332, 1333, 1334, 1335, 1336, 1337, 1338, 1339, 1340, 1341, 1342, 1343, 1344, 1345, 1346, 1347, 1348, 1349, 1341, 1342, 1343, 1344, 1345, 1346, 1347, 1348, 1349, 1350, 1351, 1352, 1353, 1354, 1355, 1356, 1357, 1358, 1359, 1351, 1352, 1353, 1354, 1355, 1356, 1357, 1358, 1359, 1360, 1361, 1362, 1363, 1364, 1365, 1366, 1367, 1368, 1369, 1361, 1362, 1363, 1364, 1365, 1366, 1367, 1368, 1369, 1370, 1371, 1372, 1373, 1374, 1375, 1376, 1377, 1378, 1379, 1371, 1372, 1373, 1374, 1375, 1376, 1377, 1378, 1379, 1380, 1381, 1382, 1383, 1384, 1385, 1386, 1387, 1388, 1389, 1381, 1382, 1383, 1384

the switch, spaced stop posts of approximately the same length secured to said base on opposite sides of the pedal support, each of said posts extending toward the recess of one of said pedal bosses and being cooperable therewith to limit the swinging movement of said pedal, and a compression spring embracing each of said posts and confined between said base and each of said pedal bosses to constantly urge said pedal toward neutral position, said springs being of similar length and strength.

NOBEL H. KOERTGE.
EDWARD L. RUCKS.
